DESIGN FOR A VASE

Ernest Oral Moncer, Huntington, W. Va.

Application December 12, 1944, Serial No. 116,867

Term of patent 14 years

(Cl. D29—28)

To all whom it may concern:

Be it known that I, Ernest O. Moncer, a citizen of the United States of America, residing at Huntington, county of Wayne, and State of West Virginia, have invented a new, original, and ornamental Design for a Vase, of which the following is a specification, reference being had to the accompanying drawing, forming a part thereof wherein:

I claim:

The ornamental design for a vase, substantially as shown.

ERNEST ORAL MONCER.
